UNITED STATES PATENT OFFICE.

PANTALEON MICHAILOWITSH RODIGIN, OF BERDIANSK, RUSSIA.

ROTARY EXPLOSION-ENGINE.

1,003,800.

Specification of Letters Patent. Patented Sept. 19, 1911.

Application filed June 22, 1910. Serial No. 588,415.

To all whom it may concern:

Be it known that I, PANTALEON M. RODIGIN, a subject of the Czar of Russia, residing at Berdiansk, on the Sea of Azof, Russia, have invented certain new and useful Improvements in Rotary Explosion-Engines; and I do hereby declare the following to be a full, clear, and exact description of the invention, such as will enable others skilled in the art to which it appertains to make and use the same.

My invention relates to improvements in rotary explosion engines, and the object of my invention is to make a simple rotary engine of the four cycle type, driven by the explosion of vapor charged air, one that will be inexpensive to build, very light, and effective in action.

With these objects in view, my invention consists in the construction and combinations of parts as hereinafter described and claimed.

In the accompanying drawings—Figure 1 is a side view of one embodiment of my invention, one half of the casing being removed. Fig. 2 is a central cross-section thereof, taken on the lines 2—2 of Figs. 1 and 3. Fig. 3 is a side view of the same, the shaft being shown in section. Fig. 4 is an edge view of the same. Fig. 5 is a side view of the same, on a larger scale, parts being broken away and parts shown in section. Fig. 6 is a cross-section taken on the line 6—6 of Fig. 5. Fig. 7 is a side view of the disk that is keyed to the shaft. Fig. 8 is a cross-section thereof on the line 8—8 of Fig. 7. Fig. 9 is a side view of the loosely mounted disk, partly broken away. Fig. 10 is a cross-section of the same on the line 10—10 of Fig. 9, and Fig. 11 is a plan view thereof.

1 represents the driven shaft, and keyed to this shaft is a disk 2. This disk is provided with two arcuate slots F therein and two radially projecting arms 3, perforated at their ends, as shown in Fig. 7, and on these projections 3 are pivotally mounted pistons. A disk 2' is loosely mounted on the shaft 1 adjacent the disk 2 and has a pair of similar arms 3' carrying pistons A'. These pistons are adapted to rotate in an annular cylinder composed of two parts K, bolted together, and having an annular groove and rib connection, as shown at L, Fig. 6, so that they will fit tightly together. Between the sections K there is a space for the reception of the keyed disk 2 and the loose disk 2'

hereinafter described. The disk 2 has a circular projecting flange 5, fitting against the edge 5' of one of the casing sections K (Fig. 6), and a packing ring M, of any suitable material, is used to form a tight joint between said cylinder section and the disk 2. A similar packing ring is used with the loose disk 2'. These disks are provided with interlocking grooves and projections 6 and 7, as shown in Figs. 7 to 10, to make the fit between them perfectly tight. The loosely mounted disk 2' is provided with pins G, fitting in the slots F of the keyed disk, so that while a certain amount of relative movement is allowed between the disks, the distance between the piston arms 3 and 3' on the respective disks has a maximum and minimum. The disk 2' has projecting from it and passing outside of the annular casing a collar 8, having a channel 9 between the ribs 10. Within channel 9 is mounted a band brake 11 of any usual or well known type.

H represents a spring, which is fastened at one end to the shaft 1 and at the other end to the cylindrical collar 8.

The disks 2 and 2' fit closely together, with the pins G in the slots F and with the circular ribs or lugs of the one engaging in the grooves of the other. Each of the disks may have mounted thereon as many pistons as desired, but the number of pistons should be the same on the one disk as on the other. In the drawing, however, I have shown only two pistons mounted on each disk, these pistons traveling in the annular cylindrical space within the casing. The collar 8 on the disk 2' is provided with an annular flange or ring 10', and in the space between this flange and the main portion of the disk are mounted radially movable bolts or stops E. These stops as shown in Fig. 5, are normally pressed outward by means of the springs 11' and have beveled heads E' so that they present a square shoulder on one side and an inclined portion on the other. The internal edge of one section of the casing K is cut away at intervals, to provide recesses 12 (Fig. 5) having each a square shoulder and a sloping face into which the heads E' snap at intervals, providing stops to prevent backward rotation of the disk 2'.

The piston casing is provided at intervals on one side with inlet pipes C and on the other side with outlet pipes D, closed in opposite directions by suitable valves (see Fig. 4). The inlet pipes C are connected to any

suitable supply of carbureted air, and the outlet pipes D may be connected to any suitable common exhaust pipe. I have shown in the drawing three of these inlet and outlet devices, but as many may be used as desired, depending usually on the size of the engine.

At equal distances between the pipes C in the annular casing, are located igniting devices B¹, B², and B³, disposed into the casing K at an angle of about forty-five degrees (Fig. 6) from the horizontal.

Any usual carbureting and lubricating means can be employed, and the currents for the sparking plugs may be supplied by a magneto-electric generator driven from the main shaft 1 and provided with a commutator, so that the ignition plugs at the points B¹, B², and B³ shall be operated at the proper times. The character J (Fig. 3) represents the point where the current is led from the magneto machine to the commutator for the three sparking plugs.

In view of the fact that motors, especially those intended to be used for flying machines, must be very small and comparatively light, and without any means for cooling the cylinder by water, the casing sections K are made as thin as possible to permit the ready conduction of heat, and to prevent fracture ribs N are provided thereon at intervals, which also aid in the cooling effect.

The operation is as follows:—The engine may be turned partially by hand, the loose disk being checked by means of the band brake 11. This separates each pair of pistons A and A', the latter being stationary, tensions the spring H, and sucks in a charge of carbureted air. The brake is then set free, whereupon the spring H acts, bringing the pistons A' toward the pistons A and compressing the charge between the pistons. When the pistons A' are at their minimum distance from the pistons A, the charge between them is ignited, current to the sparking plugs being supplied by a battery in the usual way. An explosion then takes place and the pistons A will be forced forward, carrying with them the shaft 1, the pistons A' being prevented from backward rotation by the stop or abutments E engaging in the notches 12. As soon as the pistons A pass the first exhaust valves, at which time the pistons A and A' are at the maximum distance apart, the spring H acts, forcing forward the loose disk carrying the pistons A', and forcing the exhaust gas out through one of the pipes D. As soon as the pistons A pass the pipes C, they begin to suck in a new charge, and when there is a suction period between two of the pistons there is an explosive pressure between the opposite pair, and by reason of which the pistons A' are caused to lag with respect to the pistons A.

This lagging of the pistons A' compresses the spring H, which afterward, on being released, compresses the second charge and the cycle of operations is then repeated. In the form shown on the drawings, three explosions between each pair of pistons A and A' occur during a revolution, and as many explosions as desired may occur.

I claim:—

1. In a rotary explosion engine, the combination of an annular cylindrical casing, a shaft passing centrally therethrough, a disk keyed to said shaft, a plurality of pistons carried by said disk and adapted to rotate in said casing, a disk loosely mounted on said shaft and provided with a plurality of pistons also adapted to rotate in said cylindrical casing, a spring connecting said second named disk to said shaft, and spring-pressed abutments preventing the backward motion of said loose disk, substantially as described.

2. In a rotary explosion engine, the combination of an annular cylindrical casing provided with inlet and exhaust pipes and sparking plugs, a shaft passing horizontally through the center of said casing, a disk keyed to said shaft, said disk having a plurality of pistons thereon, adapted to rotate in said cylindrical casing, and having a curved slot; a disk loosely mounted on said shaft and provided with a plurality of pistons adapted to rotate in said cylindrical casing, a spring connecting said last named disk to said shaft, said last named disk being provided with a pin engaging in the groove of said first named disk, and means for preventing the backward rotation of said loose disk, substantially as described.

3. In a rotary explosion engine, the combination of an annular cylindrical casing, a shaft passing centrally through said casing, a disk keyed to said shaft, a disk loosely mounted on said shaft, each of said disks being provided with projecting arms, pistons pivotally mounted on the arms of these two disks opposite to each other, one of said disks being provided with a curved slot and the other with a pin entering said slot, and means for preventing the backward rotation of said second named disk, substantially as described.

4. In a rotary explosion engine, the combination of an annular cylindrical casing, a shaft centrally located in said casing, a disk keyed to said shaft, a disk loosely mounted on said shaft, pistons carried by each of said disks and adapted to rotate in said cylindrical casing, and means for preventing the backward movement of said second named disk when an explosion occurs, substantially as described.

5. In a rotary explosion engine, the combination of an annular cylindrical casing, a shaft centrally mounted therein, a disk

keyed to said shaft, a disk loosely mounted on said shaft, one of said disks being provided with a curved groove and the other with a pin entering said groove, and means for preventing the backward rotation of said second named disk when an explosion occurs, substantially as described.

6. In a rotary explosion engine, the combination of an annular cylindrical casing composed of two parts bolted together, a shaft centrally mounted in said casing, a disk keyed to said shaft and provided with a plurality of pistons adapted to rotate in said annular casing, a disk loosely mounted

on said shaft and provided with a plurality 15 of pistons coöperating with said first named pistons, one of said disks being provided with a groove and the other with a pin entering said groove, means for preventing the backward movement of said second named 20 disk when an explosion occurs, a spring connected to said shaft and to said second named disk, and a band brake engaging said second named disk, substantially as described.

PANTALEON MICHAILOWITSH RODIGIN.
